CLAIM

The ornamental design for a container for holding liquid for refilling an E-cigarette device, as shown and described.

DESCRIPTION

FIG. 1 is a perspective view of a container for holding liquid for refilling an E-cigarette device, showing my new design.

FIG. 2 is top perspective side view thereof.

FIG. 3 is top plan view thereof, shown enlarged for clarity of disclosure.

FIG. 4 is bottom plan view thereof; and,

FIG. 5 is a right side elevation view of FIG. 1, where left side view is a mirror image thereof.

The broken lines in FIGS. 2 and 3 depict environmental subject matter that forms no part of the claimed design.

In the drawings, the evenly-spaced broken lines depict portions of the container for holding liquid for refilling an E-cigarette device forms no part of the claim; the dash-dot-dash lines represent boundaries of the claimed design and form no part thereof.
